UNITED STATES PATENT OFFICE

WILLIAM A. DUNLAP, OF PITTSBURGH, PENNSYLVANIA

REFLECTOR

Application filed February 23, 1929. Serial No. 341,993.

My invention is an improvement in reflectors especially designed for illumination of a definite area, in either single or multiple sections.

5 It is especially designed for illuminating the prescribed area or areas of a vertical surface, such as a bill board or the like. Such boards are usually rectangular, of various dimensions, and for the best results, should 10 be evenly lighted all over, with proper and equal distribution and without waste of light rays either beyond the surface, or by duplication as by overlapping from one section or area to an adjacent one.

15 There are many designs of reflectors made for sign and bill board lighting, but in designing most of these the important factor of the distribution of light from the light source in such a manner as to produce equal 20 intensity of light over the entire surface to be lighted, without undue loss of light, is not sufficiently emphasized, or often neglected.

This important factor is essential for correct economical lighting, but is difficult to 25 accomplish, as in most cases the light sources, employed to illuminate the sign or bill board, are hung or installed approximately on a line horizontal with the top of the sign, which results in a shorter distance from the light 30 center to the top of the sign than the distance from the light center to the base or bottom of the sign, thereby causing the light cast upon the lower part of the sign to be weaker or less than that which is cast upon the 35 upper portion of the sign.

Another serious defect in most designs of reflectors is that the distribution of direct and reflected light is so wide spread as to cause a serious loss of light by extending beyond or overlapping the surface to be illuminated.

40 One other serious defect is, that in those localities where the erection, construction, and maintenance of signs involve a considerable financial outlay, it is almost imperative that the surface be illuminated without interruption. In order to produce such continuous source other reflectors have been 45 designed having two light sources instead of one, but as these two light sources are usually

placed side by side, their focal centers not being central with the center of the reflector, distorted distribution of light results, especially when one of the light sources ceases to function.

55 In order to overcome these objections I have designed my reflector so that the direct and reflected light rays from either one or two light sources are concentrated within restricted areas, and so directed as to cause 60 equal distribution of all the light emitted.

Referring to the drawings showing certain preferred embodiments of the invention:

65 Fig. 1 is a face view of a single lamp reflector;

Fig. 2 is a vertical section on the line II-II of Fig. 1;

Fig. 3 is a transverse section on the sloping line III-III of Fig. 2;

Fig. 4 is a face view of a double light reflector, similar to Fig. 1;

70 Fig. 5 is a vertical section on the broken line V-V of Fig. 4, the lamp being shown in elevation;

75 Fig. 6 is a transverse section on the sloping line VI-VI of Fig. 5, similar to Fig. 3.

The reflector is formed in such a manner that the walls forming the sides, bottom, and rear portions, are sections of true parabolas having their foci in the center of the light 80 source, with a top or upper wall providing a straight or flat portion.

According to my improved construction, that part of the light flux emanating from the light source, other than that which projects directly on the surface to be illuminated, impinges on the several parabolic sections, and is reflected in lines parallel to the major axes of the parabolas upon which they fall, and upon the upper or straight side inclined 85 at a given angle or slope. Both the axes of the various parabolas and the angle of the upper flat side are so designed that the light reflected from their surfaces is directed to those parts of the sign which ordinarily receive the lesser or weaker light, thereby producing an 90 equal illumination over the entire surface.

95 The sides, top, and bottom of my reflector are extended outwardly from the light source to such a point as to intercept the direct and 100

reflected light rays in such a manner as to confine them within the given area and eliminate loss of light from overlapping. Referring to the drawings showing the single lamp form, the lower portion of the casing providing the reflector proper is provided with an upwardly extending shell 2 having a socket 3 for insertion of the lamp 4 in the usual way.

10 The reflector is supported outwardly in front of a bill board or the like by a supporting arm 5 of suitable length, in dotted lines, which may conveniently be in the form of a pipe or tube, coupled with the socket 3 and 15 providing a conduit for the circuit wiring, as in common practice.

The top wall or upper portion of the entire reflecting shell surrounding the lamp 4 consists of a flat section 6 extending forwardly 20 and slightly downwardly from the socket shell 2, flaring or widening laterally at each side as at 7 and merging into the annular surrounding rim by a straight horizontal edge 8.

The rear middle portion of the shell immediately behind the lamp bulb consists of a part circular parabolic reflecting section *a*, merging into and attached to the annular bottom of shell 2, arched around the lamp, and having a connecting juncture with the 30 lower and each side reflector wall as shown.

The lower reflecting section or wall *b* is of parabolic form longitudinally extending from its juncture 9 with section *a* downwardly and forwardly, widening towards the front 35 and merging into the annular surrounding rim by a downwardly curved edge 10, corresponding to the cross sectional curvature of the wall *b*.

The side reflecting sections *c* and *d* likewise 40 are of parabolic form longitudinally, extending from their juncture 9 with section *a* forwardly, downwardly and laterally at each side, corresponding to the flaring or widening degree of extension of walls 6 and *b*.

45 Sides *c* and *d* join the straight edges of upper section 6 at juncture 7, bowing outwardly on a transverse plane with corresponding interior concavity, and are brought into joined connection at juncture 11 with the 50 flaring side edge boundaries of lower section *b*, as in Fig. 1.

The side sections *c* and *d* also widen continuously towards the front and merge into the annular surrounding rim by the outwardly curved edge portions 12, corresponding to the cross sectional curvature of the walls *c* and *d*.

The front edge portion of the entire reflector unit is preferably beaded or rounded as 60 shown providing a continuous terminal boundary or edge, which boundary edge is preferably on a downwardly and rearwardly inclined plane approximately at a right angle or perpendicular to the axial center III-III 65 of Fig. 2. Such axial center is coincident

with the focal center of the lamp 4 and approximates both vertically and laterally of the reflector a median line, conforming to the plane of section II-II of Fig. 1 and to a sloping transverse plane *y-y* coincident with the line III, III, in the general direction of upper wall 6. Each of such planes emerge through the front sloping plane of the open end of the reflector at about the point *x*, Fig. 1.

70 Incidentally, such central line III, III, of the entire aggregate beam of emitted light impinges upon and corresponds to a central point in the area to be lighted, and effects a concentration of light within a limited area concentric with such central line which coincides with the focal center of the lamp or light source. Such line therefore, in my improved reflector, is the central axis of the desirable increased light intensity required in such prescribed area to overcome or neutralize undesirable greater intensities of those areas lying immediately outside of the prescribed zone of my reflector, which are otherwise present.

75 Such undesirable increased intensity is ordinarily due to overlapping of outside rays or to impingement upon similar areas of light in connection with the use of plural units of other constructions in which the entire beam is not similarly confined or restricted.

80 This latter serious objection, with the accompanying variation in continuous illumination of an entire area by a plurality of units, with its resulting inefficiency and waste, is avoided by the use of the several parabolic reflecting surfaces *a*, *b*, *c*, *d* and 6, in their assembled relationship to each other and to the light source.

85 It will be observed that the front beam emission opening of the reflector in general outline approximates a rectangle, with a straight upper horizontal boundary, the bottom and sides being somewhat concaved due to the parabolic form and transverse curvature of these walls.

90 Also that the said parabolic walls *b*, *c* and *d* merge into each other and into the rear parabolic wall *a* almost continuously, i. e., at the very obtuse junctures 11 and 9 whereby the several interior reflecting wall surfaces are practically continuous.

95 The only juncture of pronounced angularity is between the lateral boundaries of upper wall 6 and the upper boundaries of side walls *c* and *d*, at 7.

100 In designing my improved reflector I have so disposed these several reflecting surfaces as to utilize to the best advantage the angles of incidence and reflection according to the well known law.

105 Direct rays from the source of light outwardly are emitted within the several edge boundaries 8, 12, 12 and 10 for illumination of a corresponding enlarged area on the il-

luminated surface, dependent on its distance.

Reflected rays a' from reflector a extend in parallelism forwardly and downwardly through the lower middle portion of the emission opening as a composite beam against a corresponding interior section or area of the whole area being illuminated.

Reflected rays $6'$ from the entire diverging surface of upper reflector wall 6 are reflected downwardly and laterally at each side within the confining limits of upper edge 8 and side edges 12 in the form of a composite expanding beam. Such beam will be distributed evenly over the entire illuminated area, contributing its proportion of illumination thereto equally throughout the prescribed area.

Reflected rays b' from the entire diverging surface of lower reflecting wall b are reflected horizontally and laterally at each side within the confining limits of the upper and side edges in the form of a composite expanding horizontal beam.

Such beam will be distributed evenly over the upper full width portion of the illuminated area, contributing its proportion of illumination thereto equally throughout such prescribed area.

Reflected rays c' from the entire diverging surface of side reflecting wall c are reflected laterally towards the opposite side and downwardly in the form of a vertically expanding composite beam. Such beam

will be distributed evenly over the full depth of one side portion of the illuminated area, contributing its proportion of illumination thereto equally throughout such prescribed area.

Likewise rays d' from the entire diverging surface of the opposite side reflecting wall d are reflected laterally towards the opposite side and downwardly in the form of a vertically expanding composite beam.

Such beam will be distributed evenly over the full depth of the other side portion of the illuminated area, contributing its proportion of illumination thereto equally throughout such prescribed area.

The total effect of such disposition of the light, combining both direct and reflected rays, is to project upon the prescribed area a composite beam of direct and reflected rays having prescribed boundaries generally conforming to the outline of the emission opening of the reflector, and of a substantially constant value throughout.

This is because the direct rays from the lamp are themselves limited by the edges surrounding the opening in advance of the lamp, while the several beams composed of the rays reflected from the several parabolic surfaces and the top flat surface are so disposed as to be equally distributed and equally supplement such direct rays, giving a gen-

eral average increase of illumination over the whole area.

Figs. 4, 5 and 6 show a modified construction of reflector utilizing a pair of lamps $4a$ arranged side by side in sockets $3a$ within a common laterally elongated shell $2a$, above a double construction reflector. Such double reflector is in all respects generally similar to the single reflector above described except that the lower parabolic reflecting surfaces $b2$ are joined at a middle median line 13. The top wall $6a$ and the side walls $c2$ and $d2$ are substantially the same as already described, extending forwardly to the common transverse plane of the front emission opening surrounded by a terminal edge or bead $8a, 12a, 10a$, forming a continuous terminal edge.

Each such side construction, including the enclosing walls and their reflecting surfaces meeting at 13, as to the surfaces $b2-c2$ and $b2-d2$ respectively, merge backwardly into the rear reflecting walls $a2$, combine with said walls and with the shell $2a$ in the same manner above described.

In such double form of reflectors having two sources of light the rear parabolic sections $a2$ are slightly inclined so that their axes converge to a point on the surface of the sign or other illuminated area, thereby eliminating distortion of light should either lamp be extinguished, as at a'' , Fig. 6.

In such double arrangement the combined direct rays of the twin lamps $4a$ are projected outwardly, laterally and downwardly, with direct impact against the area to be illuminated, in an enlarged outline of equal light value corresponding to the outline of the surrounding edge opening of the reflector.

The reflected rays from the inner surface of the flat upper wall $6a$ are projected downwardly and forwardly as indicated at $6''$ in the same manner as has been described as to the single construction; the reflected rays b'' are reflected forwardly from the surface of lower walls $b2$; the reflected rays from each surface of side walls $c2$ and $d2$ are reflected laterally toward the opposite side of the surface area as indicated at c'' , and the reflected rays from the inner surface of opposite parabolic surface of wall $d2$ are projected in the opposition direction in the same manner.

The composite beam composed of rays a'' are reflected in parallelism in the form of double beams forwardly and downwardly from the reflecting surface of rear wall $a2$ behind the source of light in the same manner already described, with slight convergence inwardly as described.

The relative proportions of the reflecting surfaces, in such double construction, may be slightly varied, as by extending the rear walls $b2, c2$ and $d2$ upwardly at the rear

slightly beyond their previously described line of juncture with the reflecting surface walls a_2 , as indicated at 9' in Fig. 5.

Such disposition slightly reduces the value of walls a_2 with a corresponding increase in reflecting value of the lower walls b_2 and side walls c_2-d_2 , but without disturbance of the general aggregate effect, and with a resulting general average of illumination over the entire area.

The construction and utility of the reflector, either in single or double form, will be readily understood and appreciated from the foregoing description. When used as a single reflector or unit, a prescribed area of limited dimensions may be fully, evenly and completely illuminated from top to bottom or from side to side, within the limitations of the complete prescribed emitted beam.

On the other hand, a series of such individual units or reflectors may be arranged outwardly in front of and along the upper portion of a sign board or the like, properly spaced apart to avoid undue overlapping of the sides of the several main beams, with an equally complete general average of illumination throughout the whole area to be lighted.

It will be understood, of course, that the individual units may be made in various sizes or dimensions, dependent on the size and power of the source of light elements, or variously changed or modified in construction or other respects by the skilled mechanic, but that all such changes or modifications are to be understood as within the scope of the following claims.

What I claim is:

1. A reflector composed of a series of lamp enclosing walls providing an upper downwardly and forwardly sloping surface, a lower downwardly and forwardly sloping surface, and opposite side surfaces having a parabolic curvature diverging laterally and downwardly and merging into said upper and lower surfaces.

2. A reflector composed of a series of lamp enclosing walls providing an upper downwardly and forwardly sloping surface, a lower downwardly and forwardly sloping surface, and opposite side surfaces diverging laterally and downwardly and merging into said upper and lower surfaces, each of said lower and side surfaces having a parabolic curvature.

3. A reflector composed of a series of lamp enclosing walls providing an upper downwardly and forwardly sloping surface, a lower downwardly and forwardly sloping surface, and opposite side surfaces of parabolic curvature diverging laterally and downwardly and merging into said upper and lower surfaces, said lower surface extending in concave parabolic curvature formation

divergently around and away from a focal center.

4. A reflector composed of a series of lamp enclosing walls providing an upper downwardly and forwardly sloping surface, a lower downwardly and forwardly sloping surface, a rear concave reflecting surface, and opposite side surfaces having a parabolic curvature diverging laterally and downwardly and merging into said upper, lower and rear reflecting surfaces.

5. A reflector consisting of a lamp receiving casing having a lamp socket, an upper flat forwardly extending wall and a rear concave wall connected with said casing, and a bottom and opposite concave side walls each having a parabolic curvature and joined to each other and to the upper flat and rear concave walls respectively.

6. A reflector composed of a series of lamp enclosing walls providing an upper downwardly and forwardly sloping surface, a lower downwardly and forwardly sloping surface, and opposite side surfaces diverging laterally and downwardly and merging into said upper and lower surfaces, each of said lower and side surfaces being concave and having a parabolic curvature providing a reflecting surface of constantly increasing distance from an enclosed source of light.

7. A reflector consisting of a lamp receiving casing having a lamp socket, an upper flat forwardly extending wall and a rear concave wall connected with said casing, and a bottom and opposite concave side walls joined to each other and to the upper flat and rear concave walls respectively, said concave walls being of parabolic form in a direction away from a lamp mounted in the socket.

8. In a reflector as described, a socket casing provided with a lamp socket, an upper front reflecting wall connected with the front of the socket casing and extending downwardly and forwardly therefrom, a rear concave reflecting wall connected with the rear of the socket casing and extending downwardly and rearwardly therefrom, opposite concave parabolic side reflecting walls connected with the upper wall and the sides of the rear concave wall diverging laterally and downwardly therefrom, and a lower concave parabolic reflecting wall connected with the bottom of the rear concave wall and with the side walls, the upper, side and lower walls terminating in a continuous surrounding edge on a common transverse plane.

9. In a reflector as described, a socket casing provided with a lamp socket, an upper front reflecting wall connected with the front of the socket casing and extending downwardly and forwardly therefrom, a rear concave reflecting wall connected with the rear of the socket casing and extending downwardly and rearwardly therefrom, opposite concave parabolic side reflecting walls con-

- nected with the upper wall and the sides of the rear concave wall diverging laterally and downwardly therefrom, and a lower concave parabolic reflecting wall connected with the bottom of the rear concave wall and with the side walls, each of said upper, rear, side and lower walls extending divergently away from the focal center of a lamp mounted in the socket.
10. In a reflector as described, a socket casing provided with a lamp socket, an upper front reflecting wall connected with the front of the socket casing and extending downwardly and forwardly therefrom, a rear concave reflecting wall connected with the rear of the socket casing and extending downwardly and rearwardly therefrom, opposite concave side parabolic reflecting walls connected with the upper wall and the sides of the rear concave wall diverging laterally and downwardly therefrom, and a lower concave parabolic reflecting wall connected with the bottom of the rear concave wall and with the side walls, each of said rear, side and lower walls extending in concave formation divergently around and away from the focal center of a lamp mounted in the socket.
11. In a reflector as described, an elongated socket casing provided with a pair of side by side lamp sockets, an upper front reflecting wall connected with the front of the socket casing and extending downwardly and forwardly therefrom, a pair of side by side rear concave reflecting walls connected with the rear of the socket casing and extending downwardly and rearwardly therefrom, opposite concave side reflecting walls connected with the upper wall and the outer sides of the rear concave walls diverging laterally and downwardly therefrom, and a pair of lower concave reflecting walls connected together at the middle and to the rear concave walls and at opposite sides to the side walls, the upper, side and lower walls terminating in a continuous surrounding edge on a common transverse plane.
12. In a reflector as described, an elongated socket casing provided with a pair of side by side lamp sockets, an upper front reflecting wall connected with the front of the socket casing and extending downwardly and forwardly therefrom, a pair of side by side rear concave reflecting walls connected with the rear of the socket casing and extending downwardly and rearwardly therefrom, opposite concave side reflecting walls connected with the upper wall and the outer sides of the rear concave walls diverging laterally and downwardly therefrom, and a pair of lower concave reflecting walls connected together at the middle and to the rear concave walls and at opposite sides to the side walls, the upper, side and lower walls terminating in a continuous surrounding edge on a common trans-
- verse plane, each of said rear, side and lower walls extending in a concave formation divergently around and away from the focal center of a lamp mounted in each socket.
- In testimony whereof I affix my signature.
